UNITED STATES PATENT OFFICE.

HENRY V. WAGONER, OF NEW YORK, N. Y.

BOX AND METHOD OF MAKING.

1,356,895.

Specification of Letters Patent. Patented Oct. 26, 1920.

Application filed December 31, 1919. Serial No. 348,624.

To all whom it may concern:

Be it known that I, HENRY V. WAGONER, a citizen of the United States of America, residing at New York, N. Y., have invented 5 a new and useful Box and Method of Making, of which the following is a specification.

My invention relates to improvements in box coverings, both as to the article itself and as to the method of manufacture.

10 In the accompanying drawings, I have shown a preferred embodiment of my invention, but I wish it to be distinctly understood that a wide variety of modifications may be resorted to without departing from 15 the spirit and scope of the same.

In the drawings:

Figure 1 is a view of the blank representing what I may term a permanent box covering.

20 Fig. 2 is a corresponding view of another blank which I may characterize a protective covering.

Fig. 3 is an edge view of the two blanks shown in Figs. 1 and 2, illustrating their 25 relative relation when ready for application to a box.

Fig. 4 is a perspective view of the underside of a box or box cover, the same being constructed to embody my invention.

30 Fig. 5 is a side elevation diagrammatic in character, illustrative of part of the method resorted to in the practice of my invention.

1 represents the body of a box or box cover. In this instance, the said body is 35 made of pasteboard. This body is provided with a permanent covering of paper of the desired color and quality, and outside of the permanent covering is a protective covering usually of transparent or semi-transparent

40 paper, which is so applied thereto as to be securely retained thereon, or it may be easily removed therefrom without injury to the box or the permanent covering. 2 represents the main body of a permanent covering: 3, 4, 5 and 6 are flaps at the edges of said body. The flaps 3 and 5 are designed to cover the ends of the box body 1, while the flaps 4 and 6 are designed to cover the sides thereof. The extreme edges of the

50 flaps are designed to fold inside of the box body as best seen in Fig. 4. 7 represents the main body of the protective covering which is preferably made of suitable protecting material such as transparent and semi-transparent paper. 8, 9, 10 and 11 are flaps on the body 7 which preferably correspond

substantially to the flaps 3, 4, 5 and 6 respectively, excepting that the side flaps 9—11 need not be as long as the flaps 4 and 6, the latter being preferably extended 60 slightly at their ends to fold around the corners of the box body.

Heretofore in the manufacture of boxes or box covers equipped with protective coverings, it has been customary to apply the 65 protective covering by hand to the finished article having thereon the permanent covering. This is a slow, laborious, and expensive process. By my invention much time and expense is saved since I so construct the permanent and protective coverings that they are applied simultaneously. To that end, I provide means for tacking the protective covering 7 lightly to the permanent covering 2 whereby they may be 70 handled as a unit and applied to the box body at one and the same time. One convenient method of tacking the temporary or protective covering to the permanent covering is to provide a plurality of notches, 80 recesses or small holes 12, 12 which may be called openings at or near the edges of the flaps of the permanent covering. When the glue or adhesive is applied to the permanent covering, a portion of said adhesive is 85 squeezed through the openings 12 on to the surface of the protective covering 7, so that a portion of said adhesive will tack the two layers together as shown in Fig. 3, the said adhesive acting thereafter not only as a 90 means for attaching the covering 2 permanently to the box body throughout substantially the entire area of surface contact, but also operating as a means to adequately fasten the protective covering to the finished 95 article.

The adhesive material may be applied in any well known manner, for example; A stack of alternately arranged coverings 2 and 7 may be moved under a roller 15 on 100 the surface of which is applied the adhesive material. As the sheets are moved under the roller from the solid line position, indicated in Fig. 5, to the dotted line position, the adhesive is applied to the upper surface 105 of the permanent covering sheet 2, and simultaneously a small portion of said adhesive reaches the underlying protective covering sheet 7, whereby the two sheets are tacked together so that the operator may 110 easily remove the two top sheets as a unit from the stack without disturbing either

their relation to each other, or disturbing the underlying sheets of the stack. When the operator has removed the two tacked together sheets, they are then simultaneously applied to the box body 1, the corresponding flaps of the two coverings being simultaneously bent down around the sides and edges of the box body. By this method substantially the entire surface of the permanent covering is caused to adhere to the box body, whereas, the protective covering is caused to adhere to the finished article only throughout a small portion of its area. This limited adherence is sufficient for the purposes of the protective covering, and yet it makes it easy to remove said protective covering if desired without danger of injury to the underlying permanent covering.

As I have already indicated, I have not attempted herein to show the various modifications of which my invention is susceptible, but have merely shown and described it in a preferred form, it being my belief that I am the first to devise a method of manufacture which comprises applying the permanent and the protective coverings to the box body simultaneously and as a unit. Obviously this method may be carried on by hand or by appropriate machinery. I also believe that this is the first instance of securing the temporary and permanent coverings together so that they can be handled and applied as a unit to the box. I believe the article as thus made is also original.

35 I claim:—

1. An improvement in the art of box making which comprises placing a permanent box covering sheet against a protective box covering sheet, said protective sheet having a portion not covered by said permanent sheet, then applying a coating of adhesive material to the first mentioned sheet and causing some of said material to be simultaneously applied to the uncovered portion of said protective sheet to tie said sheets together so that both may be simultaneously applied to a box body.

2. An improvement in the art of box making which comprises placing a permanent box covering sheet against a protective box covering sheet said protective sheet having a portion adjacent to its edge not covered by said permanent sheet, then applying a coating of adhesive material to the first mentioned sheet and causing some of said material to be simultaneously applied to the uncovered portion of said protective sheet to tie said sheets together so that both may be simultaneously applied to a box body.

60 3. An improvement in the art of box making which comprises placing a permanent box covering sheet against a protective box covering sheet the permanent sheet having spaced passages therein adjacent to its edges

to expose corresponding portions of said protective sheets therethrough, then applying a coating of adhesive material to the surface of the first mentioned sheet and causing some of said material to be simultaneously applied to said protective sheet through said passages to tie said sheets together so that both may be simultaneously applied to a box body whereby the permanent sheet will be secured thereto throughout substantially its entire surface area and the protection sheet will be secured thereto at its edges only.

4. In the manufacture of boxes of the character described, the method applying to a box body a covering comprising, first placing two covering sheets together in proper overlying position and tacking said sheets together by a suitable adhesive at or near their edges and simultaneously applying said adhesive to substantially the entire surface of one of said sheets, then applying both of said sheets simultaneously to a box body to cause one of said sheets to be permanently secured to said body throughout substantially its entire area of surface engagement, and to cause the other sheet to be secured to the box body throughout only a very small part of the surface of said second sheet and adjacent its edges only.

5. In a box construction a box body, a permanent covering sheet therefor, a protective covering sheet, adhesive material securing the permanent covering to the box body and also securing the protective sheet to said box body and to the permanent sheet at and adjacent the edge of the latter, said protective sheet being secured to the permanent sheet before said sheets are applied to the box body by placing the permanent sheet on the protective sheet a portion of the edge of the latter being uncovered whereby the application of a coating of adhesive to the permanent sheet will cause said adhesive to simultaneously be applied to the uncovered portion of said protective sheet to thereby hold said sheets together so that they may be simultaneously applied to said box body.

6. In a box construction, a box body, a covering therefor comprising two sheets one overlying the other, the underlying sheet having passages therein adjacent its edges, the overlying sheet covering said passages, an adhesive coating covering substantially the entire surface area of the underlying sheet on the side toward the box body as well as those portions of said overlying sheet exposed through said passages, whereby the underlying sheet is secured to the box body throughout substantially its entire surface area while the overlying sheet is secured to said box body only adjacent its edges.

HENRY V. WAGONER.
